(57) **CLAIM**

The ornamental design for an embryo filter, as shown and described.

DESCRIPTION

FIG. 1, is an isometric view of the embryo filter, showing the base and separable lid of my new design;

FIG. 2, is a top view of the base thereof;

FIG. 3, is a side elevational view with its lid in place thereof;

FIG. 4, is a side elevational view thereof, rotated 90 degrees from the side elevational view of FIG. 3;

FIG. 5, is a side elevational view thereof, rotated 180 degrees from the side elevational view of FIG. 3;

FIG. 6, is a top view of the lid thereof;

FIG. 7, is a bottom view with the lid in place, thereof; and,

FIG. 8, is a bottom view of the lid thereof.
